UNITED STATES PATENT OFFICE.

FRANK A. GOODYKOONTZ, OF MIAMI, ARIZONA.

COLLAPSIBLE SHELF.

1,286,588.

Specification of Letters Patent.

Patented Dec. 3, 1918.

Application filed May 14, 1918. Serial No. 234,432.

To all whom it may concern:

Be it known that I, FRANK A. GOODYKOONTZ, a citizen of the United States, residing at Miami, in the county of Gila and 5 State of Arizona, have invented new and useful Improvements in Collapsible Shelves, of which the following is a specification.

This invention relates to a collapsible shelf, and has for its object to produce an 10 article of this character which may be easily, quickly and securely set up without the employment of auxiliary securing means, and which may be likewise detached and folded into a compact package for storage or trans- 15 portation.

In carrying out my invention it is my purpose to produce a corner shelf comprising two hinged members formed with entering prongs, one of the said members having 20 hingedly connected thereto a stay designed to engage with a rack surface of the other member to hold the said members straight in hugging contact with the angle walls of a room, each of the members being reinforced adjacent the hinged connection 25 thereof, the said reinforcements serving also as a support for a shelf, and the members being formed with hooks or other suitable projections whereby articles of clothing, 30 and the like may be supported therefrom.

I accomplish the foregoing objects and others by a simple construction, combination and arrangement of parts, a satisfactory embodiment of which being illustrated 35 by the drawings.

In the drawings,

Figure 1 is a perspective view of the improvement in its set up position.

Fig. 2 is a top plan view of the same. 40 Fig. 3 is an inner face view of the improvement, the elements comprising the same being in their open and spread condition.

While my improvement is especially desirable for transient guests in hotels, boarding houses, etc., wherein a temporary shelf and hanger for clothing or toilet articles is desirable, the improvement may, of course, remain a permanent fixture if desired. 45

The improvement may be constructed of any desired material, but preferably the same is formed of metal.

As disclosed by the drawings the improvement embodies two substantially rec-

tangular members 5 and 6 respectively which have their inner ends hingedly connected, as at 7. The knuckle of the hinge of one of the members has secured thereon an angularly extending outwardly projecting prong 8, and both of the members, adjacent the outer ends thereof are provided with similar prongs 9. The prong 8 is designed to be received in the wall of the corner of the room, and the prongs 9 in the angular side walls of the room 10'. 60

The member 5, upon its outer face, and adjacent its outer end is provided with a rack surface 10. The member 6, at its outer end has hingedly secured thereto, as at 11 a prop 70 or stay rod 12, the same comprising two sections 13 and 14 respectively, the sections being hingedly connected, as at 15, and the outer section 14 at the outer end thereof being formed with an angular surface or tooth 75 16 which is designed to be engaged between certain of the teeth of the rack surface 10 of the member 5. The hinged connection between the members 13 and 14 of the stay 12 is preferably such that the members can 80 be folded or swung away from each other in one direction only, being in the nature of a rule joint, but this, of course, is not essential as when the section 14 is arranged at an angle with respect to the section 13, as 85 indicated by the dotted lines in Fig. 2 of the drawings, and the members forced into alinement the sections 5 and 6 will be swung away from each other from their hinge 7 so that the spurs 9 will enter the side walls of 90 the room 10', the spur 8 entering the corner of the walls, and the device effectively held upon the walls.

As disclosed by the drawings each of the members 5 and 6 is provided, upon its inner 95 face with a plurality of outwardly extending hooks 17, and these hooks are designed to provide a support for toilet articles or for articles of clothing.

The members 5 and 6 are slotted from 100 their upper edges at spaced intervals and the metal bounded by the slits is bent inwardly at a substantially right angle with respect to the said members, providing horizontal ledges 18, and the outer ends of these 105 ledges are preferably flanged upwardly as at 19. The ledges provide a flat support for a shelf 20, the said shelf being preferably constructed of glass, while the flanges 19 contacting with the outer edge of the sub- 110

stantially triangular shelf 20 holds the same against outward movement upon the supporting frame.

It is believed, from the foregoing description, when taken in connection with the drawings, the simplicity and advantages of the construction will be apparent without further detailed description.

Having thus described the invention, what I claim is:

10. 1. In a corner shelf, a frame comprising two hinged members having inwardly projecting spurs, one of said members having a rack surface, a stay hingedly secured to the other member, and said stay comprising two hingedly connected members the outer one of which is designed to engage with the referred to rack surface to hold the first named members at an angle with respect to each other.
15. 2. In a corner shelf, a frame comprising two substantially rectangular members having their inner ends hingedly connected, a spur on the end of each of the members, a spur at the hinged connection between the members, hooks on the inner faces of the members, one of said members being de-

pressed to provide a rack surface on its inner face, and the outer member having a stay hingedly connected to the end thereof, said stay comprising two hinged members, a toothed surface on the end of the outer member designed to engage with the rack, when the sections of the stay are brought to alignment to hold the frame members at an angle with respect to each other.

3. In a corner shelf, a frame comprising two substantially rectangular members which are hingedly connected, spurs projecting from said members, one of said members having a rack surface, the other member having a stay rod hingedly connected to the outer end thereof, said rod comprising two hinged members, the outer member having its end formed with a tooth to engage the referred to rack, hooks on both the said members, integrally formed ledges on both of said members, flanges on the ends of said ledges, and a shelf designed to rest on said ledges and be engaged by the flanges to hold said shelf against movement in the direction of the flanges.

In testimony whereof I affix my signature.
FRANK A. GOODYKOONTZ.
